HEAT SEALING DEVICE

Harold E. Hallman, Catonsville, Md.

Application September 1, 1938, Serial No. 227,877

9 Claims. (Cl. 93—8)

My invention relates to the art of making bags of paper or other similar flexible material which has been previously coated on one or both sides with wax, paraffin, or a moisture proof coating of 5 a similar nature in order to render it resistant or impervious to grease and moisture. More specifically my invention relates to an apparatus and a method for sealing bag bottoms formed by a bottom overlap of wax coated paper.

10 Many attempts have been made to devise proper machines for sealing the bottoms of wax coated paper bags, but, because of the inherent difficulties attendant in operating with a material of this nature, such machines have been for the 15 large part commercially impractical.

It is necessary to apply sufficient heat so that the glue placed on the wax coated paper can penetrate down into the paper when the heat melts the wax to secure a proper joint. However, when pressure is applied directly on the 20 heated spot, the glue is squeezed out so that a good joint cannot be secured. However, when pressure is not employed, a proper sealing of the bag cannot be effected, nor a true moisture proof 25 seal be obtained.

I have devised a novel apparatus whereby I obtain an entire water and moisture proof seal of the bag bottoms and simultaneously effect a solid grip between the body of the bag and the overlap which forms the bag bottom.

My apparatus comprises a roll in which is placed a block having a cut out center portion, the block containing a heater preferably of the cartridge type which heats the entire block and 35 is adapted to convey heat across the cut out section. This cut out block pressure unit is adapted to contact the bag bottom so that the cut out portion is superimposed over the glue line and the pressure portions of the block press on the 40 adjacent areas to form a heat seal of the wax coated paper.

By means of this machine and its method of 45 employment the bag bottom is well pressed during the heating operation so that a good heat seal is obtained, while, at the same time, sufficient heat is imparted to the glue and the wax surrounding it so that the wax melts and the glue can penetrate to the paper which it is desired to bond. Further, the pressure units that 50 are adjacent the cut out portion prevent the squeezing out of the glue. The pressure block that presses on the extreme bottom of the bag may also be corrugated so that it crimps the extreme bottom of the bag thus providing a superior seal.

It is the object of my invention to provide a novel machine for effecting the heat sealing of wax coated paper.

It is a further object of my invention to provide a novel machine which effects the sealing 5 of wax coated paper coated with glue by the simultaneous application of pressure to the non-glue areas and heat without pressure to the glue area.

It is a further object of my invention to provide 10 a machine comprising a heated block having a cut out portion, the block adapted to press a bag bottom with the cut out portion being superimposed over the glue line of the bag bottom.

It is a further object of my invention to provide 15 a novel machine comprising a roll carrying a pressure block heated by a cartridge heater, the pressure block having a cut out center portion, which cut out center portion is superimposed over the glue line of a bag bottom and the 20 pressure portions of the block being superimposed over the non-glue areas of the bag bottom.

Further objects of my invention will be brought out in the following description of my 25 invention.

In the drawings, Figure 1 is a combination cross-section and perspective view of the machine of my invention.

Figure 2 is a cross section taken along the line 2—2 of Figure 1.

Figure 3 shows the bag that is sealed with the machine of my invention.

Figure 4 is a cross-section taken along the line 4—4 of Figure 3 and shows in diagrammatic detail the folded over bag bottom with the glue line 35 in relative position with respect to the pressure block shown in dotted lines.

Figure 5 is a perspective view of a modified form of a pressure block in reversed position to more clearly illustrate its structure. In this 40 modified form there is a provision for crimping along the bottom of the bag.

Figure 6 is a perspective of a bag having a crimped bottom pressed by the crimping pressing block shown in Figure 5.

Referring now more specifically to the drawings, in Figure 1 is shown a bag 4 drawn forward by the advancing rolls 2 and 3 in the direction indicated by the arrow. The bottom of the bag 4 is shown at the forward position under the 50 pressure block 10. Pressure block 10 is composed of the pressure portions 11 and 12 and the cut away portion 13. In the pressure block 10 is a cartridge heater 15 composed of the coil 16 wound around the insulated rod 17. Electricity 55

is conducted to the cartridge heater through the wires 20 and 21. The pressure block 10 is inset in the roll 25 at the cut away recess portion 26, and secured there by suitable securing means. 5 The roll 25 rides on the shaft 30. Cooperating with the roll 25 is the roll 35 which is adapted to rotate with the shaft 36.

Referring now to Figure 2, there is shown there in detail the manner in which the electricity is supplied to the cartridge heater and the assembly of the roll and cartridge heater. Extended from the shaft 30 is the commutator 40 on which rides the brushes 41 and 42 in the grooves 43 and 44. Electricity is supplied to the brushes 41 and 42 through the wires 45 and 46. At the sides of the cartridge heater are insulating members 48 and 49. The shaft 30 is set in the bearings 50 and 51 and rides in the bushings 52 and 53. The lower roll 35 is similarly set in bearings. 10 15 20 25 30 35 40 45 50 55 60 65 70 75

In Figure 3 is shown the bag 1 with the folded over portion 60 and the dotted lines show the glue line 61. The longitudinal seam of the bag is indicated by the overlap 63.

In Figure 4 the end of the bag in its relation to the pressure block is shown in detail. There can be seen the glue line 64 and its relative position beneath the cutaway portion of the pressure block 10 shown in dotted lines. The pressure portions 11 and 12 heat seal the bottom of the bag at 66 and 67.

As set forth hereinbefore, the pressure block 11 may be so formed, as by corrugations, as to exert a crimping action and thus crimp the bottom of the bag which it presses. Further the pressure block 12 may in certain instances be reduced to a minimum width. Such construction is employed when a sufficient heat and pressure seal is obtained by the lower pressure block and sufficient adhesion is obtained by the added adhesive. 35 40 45 50 55 60 65 70 75 80 85 90 95 100

In other words, instead of employing two pressure areas and a non-pressure area, simply a pressure area and a non-pressure area may be employed. In Figure 5 there is shown a pressure block 45 50 55 60 65 70 75 80 85 90 95 100 heated by a cartridge heater 71. The pressure block 10 has a pressure member 72 with crimping corrugations 73 running therein. On the bottom of the pressure block and positioned at the other end from the crimping member is a relatively thin pressure member 74. The pressure members 72 and 74 are separated by a cut out section 75 which is adapted to be positioned over the line of adhesive on the bag bottom, as shown in Figure 4. The heater 71 heats up the entire pressure block, and the heated crimping member 72 readily crimps the extreme bottom of the wax coated paper bag. The entire pressure block being heated, heat is transmitted through the cut out section 75 directly to the section of the wax coated paper which carries the adhesive and melts the wax coating of the paper there so that the heated adhesive strikes through to firmly bond the fibres of the paper in that area.

In Figure 6 is shown a bag 80 with a bottom 81 comprising a crimped extreme lower end 82, glue line 83 and a heat sealed relatively narrow strip 84. Sufficient adhesion is obtained by the use of crimping 82 and the heat permeated adhesive 83 so that only this thin wax to wax seal 84 is required at the top of the bottom of the bag. The crimping of the bottom being effected by means of a heated crimping member securely and effectively seals the extreme bottom of the bag so that a strong and moisture proof seal is obtained. 70 75 80 85 90 95 100

I shall now describe the operation of my ma-

chine in detail. The bag 1 is fed forward through the advancing rolls 2 and 3 which bring its forward end 4 in the position shown in Figure 4 beneath the pressure block 10. The movement of the bag and the rolls is so coordinated that the pressure block 10 moves upon the bag bottom with the cut away portion 13 of the pressure block superimposed over the glue line 64. The dotted line position of the pressure block shows the manner of engagement of the bag. The glue has previously been placed on the bag before the folding over of the bag bottom in an operation which is not being described here in detail since it is well known in the art.

As the bag moves forward under the pressure block the pressure portion 11 first tightly presses the portion of the bag indicated there as 66 in Figure 4 during which time heat is being exerted through the pressure portion 11 to effect a thorough heat sealing. Simultaneously and subsequently heat is transmitted through the block by convection and radiation to the wax paper in the area of the glue 64. This heat serves to melt the wax causing the glue to penetrate through the paper fibres and effect a bond therewith. 15 20 25 30 35 40 45 50 55 60 65 70 75 80 85 90 95 100

Thereupon the pressure portion 11 presses upon the paper at the area 67 causing a thorough heat seal of the wax at that point. In the seal of the bag bottom thus formed a strong paper to paper seal is effected by means of the glue 64 striking through the melted wax which covers the paper. At the same time a moisture proof seal is effected at the portions 66 and 67 by the dual pressing action of the pressing portions of the pressure block. The particular shape of the pressure blocks makes it impossible for the glue 64 which is in a fluid state to squeeze out, the portions 11 and 12 acting as blocks to the passage of the glue. By means of this simple construction a strong and impenetrable seal is quickly effected on the bag bottom. As has been indicated the electricity is supplied by means of a commutator and brush arrangement through the center of the shaft to the cartridge heater in this pressure block.

If desired, the pressure block may have the pressure portions 11 and 12 duplicated on the side of the pressure block, thus forming a four square pressure extension with a center cut out. In many cases this arrangement is preferable to insure against any squeezing out of the glue and to obtain a continuous heat seal about the bottom of the bag.

In lieu of the cartridge heater shown in the block any suitable heating means may be employed to raise the temperature of the block so that the pressure portions shown at 11 and 12 apply simultaneous heat and pressure to the wax coated paper while heat is transmitted over the cut away space to melt the wax adjacent the glue line.

Although I have shown a bottom drum or an engagement of the bottom of the bag in coaction with the pressure block, manifestly I may employ any suitable coacting device as for example a travelling tape. Further, although I have shown but one pressure block set in the drum I may employ a multiplicity of such units.

One of the principal features of my invention resides in the use of the pressure block having a cutaway center portion through which an intense heat is transmitted to the wax coated paper adjacent the glue without pressure. The surrounding pressure effecting the heat seal serves simultaneously to trap the glue and tends to force it into contact with the paper.

Although I have discussed apparatus and methods of my invention particularly with regard to wax coated paper, it is to be understood that I use the term "wax coated paper" by analogy only and that I intend to cover all sheet material having a heat sensitive coating that may be employed in the manufacture of articles of the class described. Thus I could employ a Cellophane base sheet material with a wax or any heat sensitive coating or I could employ any suitable sheet material with any coating material with which a satisfactory bond cannot be effected by an added adhesive. Thus in the claims that follow it is to be understood that such term "wax coated paper" is used as representative of the class of equivalents.

The application of this invention is not limited to the bag bottom sealing but is applicable to any problem wherein it is necessary or desirable to obtain a heat seal simultaneously with a glue penetration through melted coating. As can be seen the construction shown is capable of considerable modification and I intend to be limited only by the appended claims.

25 I claim:

1. An apparatus for sealing wax coated papers carrying adhesive wherein it is necessary to melt the wax to allow the adhesive to strike through to the paper comprising a rotatable body carrying a recessed pressing member having marginally positioned pressure means, means for heating said recessed pressure means, and a resilient member adapted to coact with said recessed pressing member so that a positive heat and pressure is applied to the wax coated paper by the marginally positioned pressure means and heat without pressure is applied to the area of wax coated paper carrying the adhesive thus melting the wax and causing the adhesive to strike through to the paper.

40 2. An apparatus for sealing wax coated papers carrying adhesive wherein it is necessary to melt the wax to allow the adhesive to strike through to the paper comprising a recessed pressing member having marginally positioned pressure means, means for heating said recessed pressure member, the recessed portion of said pressing member being positioned centrally, and a resilient member positioned to cooperate with the marginally positioned pressure means in pressure contact relation so that a positive heat and pressure is applied to the wax coated paper by the marginally positioned pressure means and heat without pressure is applied to the area of wax coated paper carrying the adhesive thus melting the wax and causing the adhesive to strike through to the paper.

45 55

3. An apparatus for sealing wax coated papers carrying adhesive wherein it is necessary to melt the wax to allow the adhesive to strike through to the paper comprising a rotatable body carrying a recessed pressing member, means for heating said recessed pressure member, the recessed portion of said pressing member being positioned centrally, and marginal pressing members at the edges of said recessed portion, the recessed central area being adapted to apply heat without pressure and the marginally positioned pressure members being adapted to simultaneously apply pressure with heat, and a resilient member adapted to coact with said recessed pressing member so that a positive heat and pressure is applied to the wax coated paper by the marginally positioned pressure means and heat without pressure is applied to the area of wax coated paper carrying the adhesive thus

melting the wax and causing the adhesive to strike through to the paper.

4. An apparatus for sealing wax coated papers carrying adhesive wherein it is necessary to melt the wax to allow the adhesive to strike through to the paper comprising a recessed pressing member having marginally positioned pressure means, means for heating said recessed pressure member, the recessed portion of said pressing member being positioned centrally, and a synchronously rotating pressure member rotating in pressure contact with said recessed pressing member and adapted to coact with said recessed pressing member so that a positive heat and pressure is applied to the wax coated paper by the marginally positioned pressure means and heat without pressure is applied to the area of wax coated paper carrying the adhesive thus melting the wax and causing the adhesive to strike through to the paper.

5. An apparatus for sealing wax coated papers carrying adhesive wherein it is necessary to melt the wax to allow the adhesive to strike through to the paper comprising a recessed pressing member having marginally positioned pressure means, means for heating said recessed pressure member, the recessed portion of said pressing member being positioned centrally, and a synchronously rotating rubber pressure member rotating in pressure contact with said recessed pressing member and adapted to coact with said recessed pressing member so that a positive heat and pressure is applied to the wax coated paper by the marginally positioned pressure means and heat without pressure is applied to the area of wax coated paper carrying the adhesive thus melting the wax and causing the adhesive to strike through to the paper.

6. An apparatus for sealing wax coated papers carrying adhesive wherein it is necessary to melt the wax to allow the adhesive to strike through to the paper comprising a rotating member, a pressure block mounted on said rotating member, a transverse recess extending across the external face of said pressure block substantially centrally thereof, projecting pressure members positioned on said pressure block and adjacent said transverse recess, said projecting pressure members extending across the external face of said pressure block and being substantially parallel with said recess, a cartridge heater located within said pressure block, and a cooperating and synchronously rotating resilient pressure means positioned to rotate in pressure contact with said projecting pressure members.

7. An apparatus for sealing wax coated papers carrying adhesive wherein it is necessary to melt the wax to allow the adhesive to strike through to the paper comprising a rotating member, a pressure block mounted on said rotating member, a transverse recess extending across the external face of said pressure block substantially centrally thereof, projecting pressure members positioned on said pressure block and adjacent said transverse recess, said projecting pressure members extending across the external face of said pressure block and being substantially parallel and coextensive with said recess, a cartridge heater located within said pressure block and a cooperating and synchronously rotating rubber covered roll positioned to rotate in pressure contact with said projecting pressure members.

8. An apparatus for sealing wax coated papers carrying adhesive wherein it is necessary to melt the wax to allow the adhesive to strike through to the paper comprising a rotating member, a pres-

sure block mounted on said rotating member, a transverse recess extending across the external face of said pressure block substantially centrally thereof, a forwardly positioned projecting pressure member and a rearwardly positioned projecting pressure member on said pressure block and adjacent said transverse recess, said projecting pressure members extending across the external face of said pressure block and being substantially parallel with said recess, the forwardly positioned projecting pressure member in the path of travel of the rotating member being of substantially greater width than the rearwardly positioned projecting pressure member, a cartridge heater located within said pressure block, and a cooperating and synchronously rotating resilient pressure means positioned to rotate in pressure contact with said projecting pressure members.

20 9. An apparatus for sealing wax coated papers carrying adhesive wherein it is necessary to melt the wax to allow the adhesive to strike through

to the paper comprising a rotating member, a pressure block mounted on said rotating member, a transverse recess extending across the external face of said pressure block substantially centrally thereof, a forwardly positioned projecting pressure member and a rearwardly positioned projecting pressure member on said pressure block and adjacent said transverse recess, said projecting pressure members extending across the external face of said pressure block and being substantially parallel with said recess, the forwardly positioned projecting pressure member in the path of travel of the rotating member having a crimping surface and being of substantially greater width than the rearwardly positioned projecting pressure member, a cartridge heater located within said pressure block, and a cooperating and synchronously rotating resilient pressure means positioned to rotate in pressure contact with said projecting pressure members. 20

HAROLD E. HALLMAN.
